UNITED STATES PATENT OFFICE.

CALVIN ADAMS, OF RUSSELLSBURG, PENNSYLVANIA.

IMPROVEMENT IN SAW-SWAGES.

Specification forming part of Letters Patent No. 177,447, dated May 16, 1876; application filed December 7, 1875.

To all whom it may concern:

Be it known that I, CALVIN ADAMS, of Russellsburg, in the county of Warren and State of Pennsylvania, have invented a new and useful Improvement in Saw-Sharpeners; and I do hereby declare that the following is a full and exact description of the same, reference being had to the accompanying drawings, and to the letters of reference marked thereon.

The object I have in view is the production of a simple, convenient, and effective instrument for sharpening the teeth of saws, while such teeth are in position, without the use of a file; and my invention therein consists in the novel construction and combination of the principal operative parts.

In order to enable those skilled in the art to make and use my instrument, I now proceed to describe the same, having reference to the accompanying drawings, in which—

Figure 1 is a view of the whole instrument; Fig. 2, another view, with the clasp, the key, and one of the top plates removed, and a saw-tooth in position between the dies; Fig. 3, a central section through line *xx* of Fig. 1; Fig. 4, separate views of the dies, and Fig. 5 a separate view of one of the plates.

Like letters denote corresponding parts in each figure.

In the drawings, A represents the body of my instrument, which should be made of steel, having a handle, *a*, adapted to be held in the hand, and with the outer end of the handle adapted to be struck with a hammer. The body A, preferably square in form, has fixed to its lower front end, in the manner hereinafter described, a plate, B, the inner surface of which extends upward slightly from the body A to the extreme end of such plate. A portion of one side of the body, lettered C, extends in a tongue to the front, fitting closely to the top of the plate B, and tapering on its top from the body A nearly to the end of said plate. A portion of this part C is cut away at *c*, for the purposes to be hereinafter explained. At the extreme end of the body A it is cut away in a slot, D, with enlarged circular end *d*, which passes entirely through the body A, and is recessed, as shown by the letter E, the same height as the inner end of the

part C. This recess extends only a little way in the tongue side C, so as to leave shoulders *e* above said recess, but on the opposite side the recess extends nearly to the outside of the body A, leaving a broad shoulder, *e'*, in that side. Into the recess on the tongue side C there is inserted a case-hardened steel die, F, which fits closely into the cut-away part *c*, tapering from its heel to its point, where it coincides with the line of the part C. Another die, G, of the form shown, fits into the recess in the side opposite the die F, and fills up the remaining space in such recess, and fits closely on its contiguous side to the die F. A covering-plate, H, has its end *f* made to fit into the circular opening *d*, which prevents it from moving horizontally, and in its form, size, and relative position is similar to the plate B, which is secured in place in precisely the same way. A clasp, I, of suitable metal, is adapted to slip over both plates and upon the ends of the body A. A key, J, with stops *g* at each end, and a body cut wedge-like from both ends toward the center being inserted under the clasp before the same is placed over the plates, fits into a suitable groove, *h*, in the top of the body A, and, by being driven, wedges under the clasp and holds all the parts covered by the clasp firmly in position.

It will be observed that when the dies are in position there is included between their front ends an angular space, K, which is made to conform in outline to the shape of the upper and lower cutting-faces of the tooth to be sharpened; also, that the interior faces of the plates B and H conform to the outlines of the sides of such teeth at their cutting-faces, and said dies and plates, being easily removable, may be ground down so as to answer for sharpening teeth of any form. It is also to be observed that these dies are interchangeable, so that this instrument may be used with various sizes and sorts of dies to accommodate saws of various degrees of thickness, and with various sorts of teeth.

In the use of my instrument it is held in one hand, with the key loose and placed over the tooth to be sharpened, which tooth enters between the outer ends of the plates B and H, and takes position with the upper cutting-face of the tooth pressed against the die F, and

the lower cutting-face of the tooth next to the die G. Then the key being wedged up by a blow or two of a hammer upon the end of the instrument, the cutting end of the tooth and its adjacent cutting-faces are made to assume the shape of the recess K, but the extreme cutting end is forced down into the angle which contracts and sharpens such point. At the same time the covering-plates, which coincide with the sides of the tooth at all points, hold the same from twisting, warping, or spreading, except so far as to assume the particular form desired for the tooth.

The particular advantages of my instrument are as follows: It can be used for various sizes and forms of teeth. It sharpens all teeth uniformly. It sharpens teeth perfectly without injuring the temper of the metal, as is the case in filing. It requires no special skill in its use, therefore dispensing with the need of expert filers, and is cheap and durable.

Having thus described my instrument, what I claim as new therein, and desire to protect by Letters Patent, is—

1. In a saw-sharpener, the plates B and H, substantially as described.
2. In a saw-sharpener, the combination of the dies F and G and the plates B and H, substantially as described.
3. In a saw-sharpener, the combination of the plates B and H, the dies F and G, the band I, and key J, substantially as and for the purposes set forth.

This specification signed and witnessed this 7th day of December, 1875.

CALVIN ADAMS.
